SAMPLING DEVICE

Allan T. Dahlstrom, San Leandro, Calif.

Application September 25, 1937, Serial No. 165,737

4 Claims. (Cl. 73—165)

This invention relates generally to devices for taking measured samples of various liquids. Such devices can be used to advantage in the dairy industry, for taking proportional samples of milk.

Objects of the invention can be outlined as follows: To provide a sampling device which will afford a wide range of adjustment with respect to the size of sample, without however involving the use of cumbersome or complicated structures; to provide such a device in the form of a compact portable unit, a part of which is merely dipped into a body of liquid, in taking a sample; to afford an arrangement of parts which can be readily cleaned and sterilized; to provide a novel arrangement of parts facilitating the discharge of a sample, after the same has been taken; and to afford a simple but effective indicating means suitable for setting the device for various sizes of samples.

Additional objects and advantages of the invention will appear from the following description in which the preferred embodiment of the invention has been set forth in detail in conjunction with the accompanying drawing.

Referring to the drawing:

Fig. 1 is a side elevational view, in cross-section, illustrating a sampling device incorporating the present invention.

Fig. 2 is a plan view of the indicator scale, incorporated with the device of Fig. 1.

Fig. 3 is a side elevational view, showing a development of the valve member, incorporated with the device.

Fig. 4 is a plan view showing the graduated scales applied to the rotary indicating disc, and which forms a part of the indicating means.

Fig. 5 is a cross-sectional detail, taken along the line 5—5 of Fig. 1.

The device as illustrated in the drawing consists of a container 10, which is normally retained in upright position. Secured along one side of this container 10, there is a metal shell 11, the lower end of which extends somewhat below the bottom 12 of the container 10. While the specific form of these parts may vary, it is convenient to form them cylindrical shaped, as shown in Fig. 5. The interior of the container 10 is in communication with the interior of shell 11, through the vertical extending slot 13.

Fitted within the cylindrical bore, afforded by shell 11, there is a cylindrically shaped valve member 14. The side walls of the valve member 14 are shown provided with a substantially helically formed slot or port 16, which when de-

veloped in a flat plane, can be formed as shown in Fig. 3. In Fig. 3 a portion of the slot 13 is shown in dotted lines, to illustrate the manner in which this slot cooperates with the port 16. Note that for a position such as shown in Fig. 1, 5 and illustrated diagrammatically in Fig. 3, the portions of the port which are in registry, form an opening 17 through which liquid may flow into or out of the container 10. The lower edge 16a, of the port 16, forms a weir for the opening 17, over which liquid from the container 10 may flow until the level of liquid in this container has reached a predetermined height with respect to the bottom of the container.

Valve member 14 can be adjusted angularly 15 about its axis, in order to adjust the device to take samples of different sizes. The container 10 can also be shifted in a longitudinal direction relative to valve member 14 between two limiting positions, in one of which the lower end portion of the longitudinal slot 13 is unobstructed 20 to permit free discharge of liquid from the container 10, and in the other of which the only communication between container 10 and the interior of valve member 14, is through an upper 25 portion of the slot 13 and the registering portion of port 16. Such changes in the setting of the valve member 14 are made through means which can be manipulated by an operator, from the exterior of the tank or vessel from which 30 the sample is being taken.

In the embodiment illustrated the parts described above are carried by an upper structure or body 20, which is provided with a simple handle 21. A rod 22 has its lower end connected to the upper end of the container 10, as indicated at 23, and has its upper end slidably mounted in the body 20. A small finger engaging member or trigger-shaped element 24, is secured to the rod 22, in juxtaposition to the handle 21, so that it 35 can be engaged by a finger of the operator, and pulled upwardly to elevate rod 22, together with the sampling container 10. A compression spring 25 serves to normally urge the rod 22 in a projected position, with respect to the body 20. 40 Trigger 24 is shown accommodated in a slot 26, which in turn is formed in the lower extension 27 of the body. Note that a removable ferrule or like fitting 28 is applied to the lower end of the extension 27, to limit the downward movement 45 of rod 22. By removal of the ferrule 28 the rod 22 can be removed, together with the sampling container 10.

Another rod 29 has its lower end attached to the upper end of valve member 14, and has its up- 50

55

per end journalled in the body 20. Secured to the rod 29 in the general locality of the handle 21, there is a knurled knob 31, by means of which the angular setting of the rod 29 can be adjusted.

5 In order to afford indicating means to facilitate the accurate setting of rod 29 and valve member 14, the upper end of body 20 is formed to afford a flat circular housing 32. This housing accommodates a disc 33, which is secured to the upper 10 end of shaft 29. The upper face of disc 33 is provided with a series of graduations, such as those shown in Fig. 4, and is disposed immediately below the disc 34, the peripheral edge of which is secured to the housing 32. The stationary disc or 15 cover 34 is shown provided with windows identified by letters A, B, C and D, through which the various scales on the inner disc 33, can be viewed. Also additional graduations are shown on the face of the covering disc 34, adjacent the various 20 windows, to cooperate with the respective scales on disc 33.

Operation of the device described above can now be outlined as follows: The operator grips the handle 21 and lowers the sampling container 10 into a vessel or tank from which the sample is to be taken, while the sampling container is in generally upright position. While the sampling container is being lowered into the body of liquid, the operator permits the trigger 24 to remain in substantially released position, as shown in Fig. 1, whereby liquid entering through opening 15 provided by shell 11, may flow directly into the lower portion of container 10 below the lower end of the valve member 14 and through the lower end 30 portion of slot 13. Thus while the container 10 is being lowered into the liquid, the liquid tends to surge upwardly through the container. After the container 10 has been immersed to a proper position below the level of the liquid, the operator 35 elevates trigger 24 with respect to handle 21, and such elevation causes relative longitudinal shifting movement between the shell 11 and the valve member 14. For the limiting position between these parts, which is then assumed, the lower end 40 portion of slot 13 is closed by the lower end of the valve member 14, but an upper or intermediate portion of slot 13 is now in registry with a portion of the helicoidal port 16. The operator now lifts the device from the container or vessel from which 45 the sample is being taken, taking care to maintain the sampling container 10 in substantially upright position, and to retain the trigger 24 elevated with respect to the handle 21. As the container 10 is lifted above the surface of the 50 body of liquid, a certain amount of the liquid within this container flows back through the opening formed by the registration of slot 13 with port 16, until a liquid level within this container 10 is reached, dependent upon the angular setting of the valve member 14. To discharge the sample thus obtained, the operator simply releases trigger 24, thus permitting the parts to 55 return to the relative positions shown in Fig. 1, with the result that the sample previously trapped 60 within the container 10 can now flow downwardly through the lower end portion of slot 13, and through opening 15.

It will be evident that the device described above is of extreme simplicity, and makes use of a minimum number of working parts. The parts which dip into the liquid can be readily taken apart for cleaning and sterilizing. Such a device is well adapted for taking samples of milk in proportion to the quantity of milk being collected 70 at a given point over a given period of time of say 75

twenty-four hours. For example with the graduations illustrated in Figs. 2 and 4, the device can be set by an operator to take samples proportional to the amounts of milk being collected from a given source per day, by reference to the different scales A, B, C and D. It will be evident that different graduations can be adopted, depending upon the type of service to which the device is to be employed.

I claim:

1. In a sampling device, a container adapted to be immersed in upright position into a body of liquid, a handle, means serving to connect the handle with said container, means associated with the container forming an adjustable overflow weir 10 for the same, said container being shiftable relative to said last means between two limiting positions, in one of which the container may be filled to a definite pre-determined level with a sample of liquid, and in the other of which the bottom 15 of the container is vented for discharge of liquid, means associated with the handle for effecting adjustments of said first-mentioned means, and means likewise associated with the handle for effecting relative shifting between said container 20 and said member between said two limiting positions.

2. In a sampling device for liquids, a container adapted to be immersed in a body of liquid in upright position, there being a vertically extending slot formed in one side wall of the container and extending to the bottom of the container, a substantially cylindrical shaped shell secured to one side of said container and communicating with said container through said slot, a substantially 30 cylindrical shaped valve member slidably and rotatably fitted within said shell, said valve member being provided with a spirally disposed port, means for shifting the shell longitudinally relative to the valve member between two limiting 35 positions, in one of which the lower end portion of said slot is unobstructed by the valve member to permit free discharge and ingress of liquid, and in the other of which the lower portion of the slot is closed by the valve member and in which 40 the port forms an overflow weir for the container, and means for adjusting the angular position of the valve member to vary the height of the overflow 45 weir formed by the port.

3. In a sampling device for liquids, a container 50 adapted to be immersed in upright position in a body of liquid, there being a vertically extending slot formed in one side wall of the container and extending to the bottom of the container, a substantially cylindrical shaped shell secured to one 55 side of said container and communicating with said container through said slot, a substantially cylindrical shaped valve member slidably and rotatably fitted within said shell, the periphery of said valve member being provided with a spirally 60 disposed port, a handle, a rod having its one end rotatably carried by the handle and having its other end connected to the upper end of said valve member, means likewise associated with the handle for effecting relative shifting movement of the shell longitudinally with respect to the valve member, between two limiting positions, in one of which the lower end portion of said 65 slot is unobstructed by the valve member to permit free discharge and ingress of liquid, and in the other of which the lower portion of the slot is closed by the valve member and the port forms an overflow weir for the container, and means secured to the upper end portion of said rod, in juxtaposition to the handle, to enable turning 70 75

movement of said rod with accompanying turning movement of said valve member.

4. In a sampling device for liquids, a container adapted to be immersed in a body of liquid in upright position, there being a vertically extending slot formed in one side wall of the container and extending to the bottom of the container, a substantially cylindrical shaped shell secured to one side of the container and communicating with said container through said slot, a substantially cylindrical shaped valve member slidably and rotatably fitted within said shell, said valve member being provided with a spirally disposed port forming an overflow weir for the container, the height of the overflow weir with respect to the lower end of the container being varied by changing the angular positioning of said valve member, the shell being capable of longitudinal shifting movement relative to the valve member between

two limiting positions, in one of which the lower end portion of said slot is unobstructed by the valve member to permit free discharge and ingress of liquid, and in the other of which the lower portion of the slot is closed by the valve member and the port forms an overflow weir for the container, a handle, a rod having its upper end journalled with respect to the handle and having its other end secured to one end of the valve member, and another member extending parallel to said rod, said last member having its lower end secured to the container and having its upper end slidably carried by the handle, and means engageable by the finger of an operator for sliding said last named member relative to the handle, whereby said valve member is shifted between said two positions.
